Design No. 503.

Mr. A. Allen

Improved Stand for Camera

New York 1852

Des. 503

W. A. Allen of New-York N. Y.
Letter Patent No 503 Dated Sept 21. 1852

The schedule referred to in these Letter Patent and making part of the same
To all whom it may concern:

Be it known that I W. A. Allen of the City, County and State of New York have invented or produced a new and ornamental design for embellishing stands for cameras, and other purposes and I do hereby declare the following to be a full description of the same.

The nature of my invention consists in arranging and combining with the base and column of the stand a set of designs composed of foliage and flowers for ornamenting the feet and column of the stand and a set of portraits between the feet

of the base so as to produce by the combination a complete ornamental design for the same.

But to describe my invention more particularly I will refer to the accompanying drawings or engravings of the same, the same letters where ever they occur referring to the same parts -

Figure 1 represents a perspective view of the stand

" 2 is a view of the base having three feet, the middle or centre part of which is flat and surrounded by a raised bead curled up at their lower ends and resting upon the curled ^{cup} of a transverse raised bead forming thereby a shield of the centre of the feet - at the sides of the shield are two leaves a.a. the stems of which are flat and form a beveling edge to the shield and as they run down gradually branch off from the shield so as to form toes of the curled leaves b.b at their ends.

From the sides of the shield piece at its conjunction with the middle part of the base are also scrolls c.c.

Branching from the toe of the shield piece is a stem d, d on which is a small rose e.e. surmounted by a small bud and two branching leaves from between which a large bud f extends supporting a branch of flowers g to complete the design for the feet. Between each of the feet is a medallion female portrait surrounded by a raised scroll border and having radiating crowns surmounting their brows.

Letter h is the column adjusted in the centre of the base by a screw and having a cup of leaves R. surrounding its base. From the sides of the cup a stem m, shoots upwards composed of a leaf and an open bud having a branching stem from between which a knotted stem shoots upwards to unite with the tendrils of two leaves p.p. clustering around the neck of the column. above those leaves is a cap r, formed of leaves having their points downwards which surmounts the column and completes the entire design for the stand. Letter s is a wheel placed on the head of the column, to operate the elevator screw & working into the centre of the column and supporting the table for the camera.

Having now described my invention and the peculiarities of my design, I will proceed to state what I claim and desire to secure by letter patent what I claim therefore is the design & configuration of the several ornaments forming in combination an ornamental stand for cameras and other purposes as described and set forth.
